UNITED STATES PATENT OFFICE.

BURTON J. ROBERTSON AND RAY FRAZER, OF MINNEAPOLIS, MINNESOTA, ASSIGNEES
TO LYLE CORRUGATED CULVERT COMPANY, OF MINNEAPOLIS, MINNESOTA, A COR-
PORATION OF MINNESOTA.

MILLING-MACHINE.

1,237,388.

Specification of Letters Patent. Patented Aug. 21, 1917.

Application filed June 23, 1916. Serial No. 105,457.

To all whom it may concern:

Be it known that we, BURTON J. ROBERTSON and RAY FRAZER, citizens of the United States, residing at Minneapolis, in the 5 county of Hennepin and State of Minnesota, have invented a certain new and useful Improvement in Milling-Machines, of which the following is a full, clear, concise, and exact description, reference being had to the 10 accompanying drawings, forming a part of this specification.

The present invention provides a machine for cutting in desired material a reproduction 15 of a prepared form, and the machine of our invention is primarily designed for manufacturing metal signs such as are used for street and highway guides by cutting the desired characters in a sheet of metal in conformity with previously formed guide 20 characters.

These general objects and purposes of the invention, as well as other and related objects, will more fully appear in the following detailed description and drawings.

25 In the drawings Figure 1 is an elevational view partly in section of a machine embodying our invention;

Fig. 2 is a top plan view of the machine; Fig. 3 is a broken vertical sectional view 30 of one form of guide device forming part of the invention;

Fig. 4 is a broken elevational view of the guide device shown in Fig. 3;

Fig. 5 is a plan view of a sign adapted to 35 be produced by the machine embodying our invention;

Fig. 6 is a sectional view of the sign on the line $a-a$ of Fig. 5;

Fig. 7 is a perspective view of the guide 40 characters employed with the guide device illustrated in Figs. 3 and 4;

Fig. 8 is a fragmentary elevational view 45 of another form of guiding and feeding mechanism for the machine;

Fig. 9 is a horizontal sectional view taken along the line 9-9 of Fig. 8 looking in the direction indicated by the arrows;

Fig. 10 is a fragmentary end elevational 50 view of another form of guiding or feeding device; and

Fig. 11 is a fragmentary elevational view of a roller which may be employed in the device illustrated in Fig. 10.

Similar characters of reference refer to 55 similar parts throughout the several views.

The machine embodying our invention is

in its preferred form necessarily comparatively large and heavy and, therefore, comprises a base 1, which is desirably a steel I beam mounted on a concrete foundation, on 60 which is secured the bed plate 62. A vertical standard 2 is secured on the base 1 and a post 3 is secured in the same base and in a horizontal arm with which the standard 2 is provided. An arm 4 is pivotally mounted 65 on the post 3 and an arm 5 is secured to the arm 4 on a pivot 6 removed from the post 3. At the outer end of the arm 4 an arm 7 is secured to the arm 4 on a pivot 8 and an arm 9 is secured to the arm 5 on a pivot 10 and 70 to the arm 7 on a pivot 11, the distance between the pivots 6 and 8 being the same as that between the pivots 10 and 11 and the distance between the pivots 6 and 10 being the same as that between the pivots 75 8 and 11.

A bearing sleeve 14 is secured in bearing clamps 15 and 16 secured to the arm 5 and is vertically slidable in the bearing clamps. A shaft 17 is rotatably secured in the bearing sleeve 14 and carries at its upper end a pulley driven by a belt 18 from a pulley on a shaft 68 in the pivotal bearing 6 which in turn is driven by the belt 19 from a pulley 20 on a shaft 69 in the post 3, the pulley 20 85 being driven from any suitable source of power. At its lower end the rotatable shaft 17 carries a cutting tool 21 of any desired form, but this tool is preferably a milling cutter. A rotatable screw 22 is secured between the bearing clamps 15 and 16 and is engaged by a nut 23 secured to the bearing sleeve 14 so that by rotation of the screw the bearing sleeve may be raised or lowered. An adjustable screw 24 is threaded in the 90 lower bearing clamp so that its head lies in the path of movement of the nut 23 and acts as a gage to limit the downward adjustment of the bearing sleeve.

The adjusting screw 22 is operated 100 through sprocket 25 secured to the screw by means of chain 26 which passes over a sprocket 27 on the arm 7 from which a chain 28 passes around a second sprocket 29 operable by a hand wheel 30.

105 A vertical shaft 31 is rotatably mounted in the pivot 11 and is driven by a belt 63 from a pulley on the shaft 17. A bearing 32 is secured to the arm 7 preferably in bearing clamps 33 and is vertically movable 110 therein, its vertical movement being guided and its rotation being prevented by engage-

ment of a slot 35 in the bearing 32 with a pin 36 in the clamp. A bearing 34 is mounted in the bearing 32 so that it is free to swivel therein, and the shaft 37 is rotatably mounted in the swiveling bearing 34, the latter being held against longitudinal movement on the shaft by the collars 38 and 39. At its upper end the shaft 37 carries a pulley 40 which is driven by a belt 64 from a pulley on the shaft 31. At its lower end the shaft 37 carries a worm 41 which engages a worm gear 42 mounted on a shaft 43 in a frame 44 carried by the swiveling bearing 34. The shaft 43 also carries a spur gear 45 meshing with a gear 46 on shaft 47 in the frame. In one form of guide or feed device the shaft 47 carries a grooved wheel 48 the sides of the groove of which are provided with teeth 49. A spring 50 secured to the clamp 33 and to a collar 51 on the bearing member 32 tends to retain the latter in depressed position. This member, carrying with it the swiveling bearing and shaft, may be raised by the lever 52 pivoted to the clamp 33 by means of a link 53 pivoted to the member 32 and to the lever 52.

In operation previously provided characters are secured to the bed plate 62 of the machine below the guide device carried at the outer end of the arm 7. These form characters are preferably cast iron sections 54 secured to a plate 55 with a space 56 between adjacent surfaces of the sections. The sheet of metal or other material 57 in which the characters are to be cut is secured on the bed plate 62 by any suitable clamps 65. The operator then operates the hand wheel 30 to bring the cutting tool 21 down to the desired depth in the material and this is facilitated by first setting the gage 24 so that the tool will be at the desired depth when the nut 23 contacts with the gage 24. The operator next raises the handle of the lever 52 which raises the guide device, including the wheel 48. Vertical movement of the swiveled bearing 34 in the bearing member 32 is prevented by the frame 44 which engages the lower end of the member 32 and by a pin 66 which engages a circumferential groove 67 which prevents relative vertical motion but allows the inner bearing to swivel. The arms are swung on the pivots at 6 and 8 and the bearing member 34 swiveled in the bearing 32 until the wheel 48 is aligned over the selected section of the first form character. The lever is then released and the wheel descends into contact with the selected section of the form character. The wheel 48 through the described pulleys and belts, or other suitable power transmission, is being rotated and its teeth will bite the form character and cause it to move along on the form, it being understood that after one section has been traversed the operator will lift the device and position it on

another section of the form. At the same time the cutting tool 21 is being rotated by power transmitted as described or in any other desirable way. The distance between the pivots 6 and 8 is the same as the distance between the pivots 10 and 11 and also the distance between the pivots 6 and 10 is the same as that between the pivots 8 and 11 so that any movement of the guide device around the form characters will be reproduced on a reduced scale by the cutting tool which thus cuts in the material secured below it a reproduction of the characters which are being traversed by the guide wheel 48. To permit of adjustment of the pantograph the pivots 8 and 11 and the bearing 32 are adapted to be moved longitudinally of their arms by slidably mounting the pivots and the bearing upon their arms 4, 9, and 7.

In the guiding mechanism illustrated in Figs. 8 and 9 a pointer is employed at 70 carried by the frame or bracket 44^a. This bracket, together with the gears carried by it, is similar in all respects to the bracket 90 illustrated in Figs. 3 and 4, except that the bracket contains the extension shown to support the pointer. The pointer 70 is arranged to fit into a depressed form or, in other words, a form containing grooves corresponding with the characters to be cut by the machine. Mounted directly behind and centrally located with respect to the pointer 70 is a friction roller 71 arranged, as most clearly illustrated in Fig. 9, to extend over the slot provided in the prepared form and ride upon the flat surface thereof. In the operation of the device the roller 71 is rotated in a clockwise direction (Fig. 8) so that the pointer 70 is moved forwardly 105 ahead of the roller. The pointer 70 is located concentric with the shaft 37^a so that the path taken by the milling cutter is exactly the same as the path of movement taken by the pointer 70 except that the path of movement of the cutting tool is on a different scale than that of the pointer.

In Fig. 10 the roller 71^b is provided with a central ridge 72 which serves the purpose of the pointer in Figs. 8 and 9. In Fig. 11 the roller 71^c is provided with a ridge having bevel sides instead of rounded sides, as illustrated in Fig. 10, and is arranged to ride within the grooves of a prepared form similar to the form illustrated 120 in Figs. 8 and 9. The rollers 71^b and 71^c are positioned directly under the shaft 37^b as is the roller 48 in Figs. 3 and 4.

The sign 57, which may be admirably manufactured by the machine described, has 125 cut in its surface sinuous grooves 58 forming the desired characters. These grooves 58, by reason of having been cut by the power driven milling tool, or other suitable tool, 21, are formed with a substantially vertical 130

and continuous and unbroken side wall 59 and the grooves, if desired, may be formed with a central depression 60. The whole sign may be provided with a decorative border 61 if desired.

Having thus described our invention what we claim as new and desire to secure by Letters Patent of the United States is:

1. In a machine for forming in desired material a reproduction of a prepared form the combination of a pantograph, a rotary milling cutter on the reproducing arm thereof, means for rotating the cutter, a roller provided on the tracing arm of the pantograph arranged to engage a reproducing form and means for rotating the roller to feed the same over the form.

2. In a machine for forming in desired material a reproduction of a prepared form the combination of a pantograph, a rotary milling cutter on the reproducing arm thereof, means for rotating the cutter, a roller swiveled on the tracing arm of the pantograph arranged to engage a reproducing form, and means for rotating the roller to feed the same over the form.

3. In a machine for forming in desired material a reproduction of a prepared form the combination of a pantograph, a reproducer carried on the reproducing arm thereof, a roller provided on the tracing arm of the pantograph arranged to engage a form, and means for rotating the roller to feed the same over the form.

35 4. In a machine for forming in desired material a reproduction of a prepared form the combination of a pantograph, a reproducer carried on the reproducing arm thereof, a roller swiveled on the tracing arm of the pantograph, and arranged to engage a form, and means for rotating the roller to feed the same over the form.

5. In a machine for forming in desired material a reproduction of a prepared form the combination of a pantograph, a reproducer provided on the reproducing arm thereof, a shaft journaled in the tracing arm, a power shaft journaled at the fixed point of the pantograph, transmission mechanism connecting said shafts, said mechanism extending from the power shaft to the tracing arm shaft around the arms of the pantograph, and means operable by the shaft journaled in the tracing arm for feeding the arm over a prepared form.

6. In a machine for forming in desired material a reproduction of a prepared form the combination of a pantograph, a shaft journaled in the tracing arm thereof, a shaft journaled in the reproducing arm, a milling cutter connected with the last mentioned shaft and forming the reproducer of the pantograph, a power shaft journaled at the fixed point of the pantograph, transmission mechanism interposed between said shafts,

said mechanism extending from the power shaft to the reproducer shaft and tracing arm shaft around the arms of the pantograph, and means operable by the shaft journaled in the tracing arm for feeding the 70 arm over a prepared form.

7. A machine for forming in desired material a reproduction of a prepared form, comprising a pantograph, a shaft journaled in the tracing arm thereof, a worm carried 75 by said shaft, a bracket swiveled in the tracing arm concentric with and arranged to rotate in a plane normal to the axis of said shaft, a worm wheel journaled in the bracket and adapted to mesh with said worm, a feed roller carried by the bracket and rotatably connected with said worm wheel, said feed roller being arranged to travel over a prepared form, and means for 80 rotating said shaft.

8. A machine for forming in desired material a reproduction of a prepared form comprising a pantograph, a shaft journaled in the tracing arm thereof, a worm carried 90 by said shaft, a bracket swiveled in the arm concentric with and arranged to rotate in a plane normal to the axis of said shaft, a worm wheel journaled in the bracket and adapted to mesh with said worm, a feed roller carried by the bracket, transmission 95 gearing extending from the worm wheel to the feed roller, said feed roller being arranged to travel over a prepared form, and means for rotating said shaft.

9. A machine for forming in desired material a reproduction of a prepared form comprising a pantograph, a shaft journaled in the tracing arm thereof, a worm carried by said shaft, a bracket swiveled in the arm concentric with and arranged to rotate in a plane normal to the axis of said shaft, a worm wheel journaled in the bracket and adapted to mesh with said worm, a feed roller carried by the bracket and rotatably connected with said worm wheel, said feed 100 roller being arranged to travel over a prepared form, means for rotating said shaft and devices for simultaneously moving both the bracket and the shaft in a longitudinal direction.

10. In a machine for forming in desired material a reproduction of a prepared form the combination of a pantograph, a reproducer carried on the reproducing arm thereof, and a roller on the tracing arm of the 110 pantograph, said roller being provided with a peripheral groove, and adapted to move over a ridge form arranged to be straddled by the roller to guide the tracing arm of the pantograph.

11. In a machine for forming in desired material the reproduction of a prepared form, the combination of a pantograph, a reproducer carried on the reproducing arm thereof, and a roller provided on the tracing 120

arm of the pantograph, said roller being provided with a toothed peripheral groove, and adapted to move over a ridge form arranged to be straddled by the roller to guide 5 the tracing arm of the pantograph.

12. A machine for forming in desired material a reproduction of a prepared form comprising a pantograph, a shaft journaled in the tracing arm thereof, a worm carried 10 by said shaft, a bracket swiveled in the tracing arm concentric with and arranged to rotate in a plane normal to the axis of said shaft, a worm wheel journaled in the bracket and meshing with said worm, a 15 feed roller carried by the bracket and connected with said worm wheel, said feed roller being provided with a peripheral groove arranged to straddle a prepared form, and means for rotating said shaft to 20 feed the roller over the form.

13. In a machine for forming in desired material a reproduction of a prepared form the provision of a pantograph structure, a reproducer provided on the reproducing 25 arm of the pantograph, a tracer mounted on the tracing arm of the pantograph, a work holder mounted under the reproducer, means for moving the reproducer relatively to the pantograph toward or away from the work 30 holder, and devices for operating said means, said devices being located on the tracing arm of the pantograph whereby the tracer and reproducer may be controlled from the tracing arm of the pantograph.

35 14. In a machine for forming in desired material a reproduction of a prepared form, the provision of a pantograph structure, a rotary milling tool provided on the reproducing arm of the pantograph, a tracer 40 mounted on the tracing arm of the pantograph, a work holder mounted under the tool, means for moving the tool relatively to the pantograph toward or away from the work holder, and devices for operating said 45 means, said devices being located on the tracing arm of the pantograph whereby the tracer and tool may be controlled from the tracing arm of the pantograph.

50 15. In a machine for forming in desired material a reproduction of a prepared form, the provision of a pantograph structure, a power driven tool mounted on the reproducing arm of the pantograph, a power driven tracer mounted on the tracing arm 55 of the pantograph for moving the tracing arm over a stationary form, a work holder disposed under the tool, means for moving the tool relatively to the pantograph toward or away from the work holder, devices 60 for operating said means, said devices being positioned on the tracing arm of the pantograph in proximity to said power driven tracer, and mechanism for moving the tracer

relatively to the pantograph toward or away from its coöperating stationary form.

65

16. In a machine for forming in desired material a reproduction of a prepared form, the provision of a pantograph structure, a power driven tool mounted on the reproducing arm of a pantograph, a power driven tracer mounted on the tracing arm of the pantograph, said tracer including a roller arranged to be driven over a stationary form, a work holder disposed under the tool, means for moving the tool relatively to the pantograph toward or away from the work holder, devices for operating said means, said devices being positioned on the tracing arm of the pantograph in proximity to said power driven tracer, and mechanism for moving the tracer relatively to the pantograph toward or away from its coöperating stationary form.

70

17. In a machine for forming in desired material a reproduction of a prepared form, 85 the provision of a pantograph structure, a rotary milling tool provided on the reproducing arm of the pantograph, a tracer mounted on the tracing arm of the pantograph, a work holder mounted under the tool, means for moving the tool relatively to the pantograph toward or away from the work holder, mechanism for limiting the movement of the tool toward the work holder whereby the depth of the cut portion of the work may be maintained constant, and devices for operating said means, 90 said devices being located on the tracing arm of the pantograph whereby the tracer and tool may be controlled from the tracing 100 arm of the pantograph.

95

18. In a machine for forming in desired material a reproduction of a prepared form, the provision of a pantograph structure, a reproducer provided on the reproducing arm of the pantograph, a work holder disposed under the reproducer, a tracer mounted on the tracing arm of the pantograph and arranged to trace a previously prepared form, means for moving the reproducer relatively to the pantograph toward or away from the work holder, and devices for moving the tracer relatively to the pantograph toward or away from the form which it is arranged to trace, said means and devices 115 being mounted on the pantograph structure in close proximity to one another so that either one or both may be controlled by the operator from one side of the machine.

105
